Des. 187,477
Patented Mar. 22, 1960

187,477

CASING FOR AN AMUSEMENT GAME APPARATUS OR SIMILAR ARTICLE

Thomas K. Hale, Glendale, Calif., assignor to Harrah's Club, Reno, Nev., a corporation of Nevada

Application September 18, 1959, Serial No. 57,597

Term of patent 14 years

(Cl. D34—5)

Fig. 1 is a perspective view of a casing for an amusement game apparatus showing my new design;

Fig. 2 is a front elevational view;

Fig. 3 is a back view;

Fig. 4 is a side elevational view; and

Fig. 5 is a bottom view thereof.

I claim:

The ornamental design for a casing for an amusement game apparatus or similar article, substantially as shown.
